(57) **CLAIM**

We claim the ornamental design for a water sensor ornament, as shown and described.

DESCRIPTION

FIG. 1 is a front, right perspective view of a water sensor ornament showing our new design;

FIG. 2 is a front elevational view thereof; and,

FIG. 3 is a right side elevational view thereof, a left side elevational view being a mirror image thereof.

Environmental structure including container portions, and portions of a wire that is broken away to indicate indeterminate length, shown in broken lines, form no part of the claimed design.

All sides and other portions not shown form no part of the claimed design.

The design as depicted in FIGS. 1-3 shows radially extending portions arrayed symmetrically about an imaginary axis extending through a centerpoint of the design.
